JIG

George C. Crangle, San Francisco, Calif.

Application August 20, 1938, Serial No. 225,885

7 Claims. (Cl. 209—455)

This invention relates in a general way to the recovery of minerals from ores, and has particular reference to pulsators or jigs for separating the ore-bearing part of material from gravel and the like.

One object of the invention is to provide an apparatus of the character indicated, which is simple in construction and highly efficient in operation.

A further advantage is that the apparatus can be operated over a considerable period of time without repairs or replacement of parts. This advantage is highly important because devices of the kind are usually employed in locations where repairs and replacements are difficult.

More specifically, the invention provides a highly efficient seal for confining operating pressures in such a manner that they will be efficiently directed through the screen.

With the foregoing and other objects in view, 20 the invention consists of a novel construction and relation of parts, one embodiment of which will be hereinafter described with reference to the drawing accompanying and forming a part of the specification.

The construction shown in the drawing comprises a screen 10 of any suitable construction for the intended purpose, and supported in any suitable manner within the sheet metal shell 11 which may be of any suitable shape. The upper end of the shell is riveted to angle irons 12 which are bolted as at 13 to any suitable support or framework 14. Mounted below the screen is what is usually referred to herein as a hutch 15. This hutch comprises a conical bottom and a cylindrical wall 16 which extends upward and an extension of that wall 17 extending downward. Spaced from the walls 16, 17, is another wall 18 and a bottom 19 connecting the wall 17 forms a narrow, deep receptacle integral with the hutch 15. The sheet metal shell 11 supporting the screen has a downwardly extending skirt 21 which, in assembling, is inserted between the walls 17 and 18. The relation of the parts, when assembled, is about that shown in the drawing at the end of an upstroke of the hutch 15 and parts moving with that hutch.

The receptacle comprising the walls 17 and 18 is filled for about half of its depth with mercury 20 before the skirt 21 is inserted between the walls 17 and 18. Integral with the hutch 15 is a rod or shaft 23 sliding in a bearing 24. Connected to the lower end of the rod 23 is a member 25 which also surrounds an eccentric 26 fixed on the rotatable shaft 27. When the shaft rotates the 55

hutch 15 and all parts integral therewith will be reciprocated up and down.

As the material which is to be jigged or pulsated on the screen 10 is water borne, the hutch will be filled with water as well as screenings, and the reciprocation of the hutch will jig or pulsate the material on and above the screen. This will involve applying pressure to the underside of the screen during the upward movement of the hutch 15 and a downward flow toward and through the screen when the hutch 15 is lowered. During this application of pressure and release of pressure or retraction of the hutch, the mercury will first be driven down around the bottom of the skirt and up around the outside of the skirt 21 depending from the screen support and then back up along the interior wall of the skirt. In this way the jiggling or pulsating pressure to and through the screen is yieldingly confined under the screen and this effect is produced without having to use close-fitting sliding bearings which might be quickly destroyed by sand and grit in the material being screened.

As an additional safeguard, although not an essential one, the sheet metal shell 11 may have attached to its interior a member 31 formed inward and then downward to provide a shield which will keep coarse material out of the receptacle for the mercury.

30 The lower end of the hutch may be provided with a spout 32 and valve 33 to permit withdrawal of the metal-containing screenings accumulated in the bottom of the hutch.

35 The shape of the sheet metal shell and the shape of the screen may be varied. In fact, the upper part of the shell above the screen may be in the form of a chute or conduit through which the material may be flowed over the screen to subject it to the jiggling action brought about by the reciprocation of the hutch. This may involve inclining the screen at a slight angle.

40 It is obvious, of course, that the hutch and parts associated or integral with it may be held stationary, and the support for the screen given a movement to lift the screen up and down to agitate or jig the material on and above the screen.

45 While the structure shown and described is adapted to fulfill the purposes primarily stated, it is not the desire to be limited to that embodiment, as the invention is capable of various modifications with suitable changes in the structure and relation of parts, all of which come within the scope of the claims which follow.

What is claimed is:

1. In an apparatus of the character described,

a screen for water borne material and a support for the screen, a member below the screen for receiving the screenings, means for effecting a relative movement of the screen support and said member and thereby pulsating or jiggling the material on the screen, and a mercury seal between said support and said member comprising relatively movable members including a receptacle for mercury, and a supply of mercury in said receptacle sufficient to maintain a seal between said member and below the screen during all parts of said relative movements.

2. A device of the character described comprising a screen for water borne ore containing material and a hutch below the screen, means for effecting a relative movement of the hutch and screen to jig the material on the screen, and a seal between the screen and hutch comprising a pair of spaced apart parallel walls united at the bottom to form a narrow and deep receptacle integral with the hutch, a member integral with the screen including a skirt inserted between the walls of the receptacle and extending well down in the receptacle, and mercury in the receptacle in sufficient quantity to flow back and forth around the lower edge of the skirt while maintaining a seal around said edge during the aforesaid relative movements.

3. A device of the character described comprising a screen and a support therefor including a hopper above and surrounding the screen, a reciprocatory hutch below the screen, a receptacle around the hutch comprising spaced apart parallel or concentric walls, a member integral with the screen support including a skirt extending down between said walls, means for reciprocating the hutch to jig ore bearing material passing over the screen, and mercury in said receptacle in sufficient quantity to maintain a yielding seal of the lower edge of the skirt during the reciprocations of the hutch.

4. In an apparatus of the character described, a screen for water borne ore bearing material and a support for the screen, a member below the screen constructed to hold water received from said material and to receive the screenings, means for effecting a relative movement of the screen support and said member to apply a pulsating or

jigging movement to the material above the screen, and a mercury seal comprising relatively movable members on the screen support and said member including a receptacle containing enough mercury to maintain a seal between the screen support and said member at all times during said relative movements.

5. In an apparatus of the character described, a screen for water borne ore bearing material, a hutch movable up and down below the screen to jig material above the screen, a narrow and deep receptacle around and integral with the hutch, a support for the screen, an impervious member extending down from the screen support into said receptacle, and a supply of mercury in said receptacle sufficient to maintain a seal around the lower edge of said impervious member whereby to confine the jiggling effect to the screen and the material above the screen.

6. A jiggling apparatus comprising a screen for the material to be jiggled and a support for the screen, a reciprocatory hutch below the screen, a receptacle around and integral with the hutch comprising spaced apart or concentric walls, a member integral with the screen support including a skirt extending down between said walls and a shield extending down over the inner one of said walls, means for imparting jiggling reciprocation to the hutch, and a supply of mercury in said receptacle sufficient to maintain a seal around the lower edge of the skirt during the reciprocations of the hutch.

7. A jiggling apparatus comprising a screen for the material to be jiggled and a support for the screen, a reciprocatory hutch below the screen, a receptacle around and integral with the hutch comprising spaced apart or concentric walls, a member integral with the screen support including a skirt extending down between said walls, means for imparting jiggling reciprocation to the hutch, and a supply of mercury in said receptacle sufficient to maintain a seal around the lower edge of the skirt during the reciprocations of the hutch, said mercury flowing in either direction around said lower edge to extents varying with pressures between the hutch and the screen.

GEORGE C. CRANGLE.
